DEVICE FOR CONTAINING AND APPLYING COSMETICS

Mona V. Eastley, Los Angeles, Calif., assignor to Charles A. Mureau, Los Angeles, Calif.

Application September 13, 1938, Serial No. 229,681.

17 Claims. (Cl. 132—79)

This invention relates to cosmetic handling and applying devices and relates more particularly to a device for containing and applying mascara, rouge, etc. A general object of this invention is to provide a practical, effective and very convenient device of the character mentioned.

Another object of this invention is to provide a cosmetic applicator containing a supply of cosmetic and an easily accessible and readily manipulable brush for applying the cosmetic.

Another object of this invention is to provide a cosmetic containing and applying device of the character mentioned that may be used and carried about without danger of soiling the hands, clothing, etc. and without the loss of the cosmetic.

Another object of this invention is to provide a device of the character mentioned in which the brush is supported in a novel and effective manner so that it is securely held against displacement and loss and yet is readily accessible and easily removed for use.

Another object of this invention is to provide a device of the character mentioned in which the cosmetic is supplied to the device in the form of a replaceable insert or filler that may be easily and quickly replaced when exhausted.

Another object of the invention is to provide a device of the character described adapted to contain two supplies of cosmetics differing in shade or character and embodying means for removing the excess cosmetic from the brush following its use, whereby the brush may be subsequently employed to apply either of the cosmetics.

A further object of this invention is to provide a cosmetic applying device of the character mentioned that embodies a mirror associated with the body of the device to be available for use when the brush is being employed to apply the cosmetic.

The various objects and features of my invention will be fully understood from the following detailed description of typical preferred forms and applications of the invention, throughout which description reference is made to the accompanying drawings, in which:

Fig. 1 is an elevation view of the rear side or under side of the device. Fig. 2 is an edge elevation of the device. Fig. 3 is a top or plan view of the device showing the cover in a partially open position. Fig. 4 is an enlarged longitudinal detailed sectional view of the device with the cover in the closed position. Fig. 5 is an enlarged plan view of the brush removed from the device showing the outer portion of the brush in longi-

tudinal cross section. Fig. 6 is an enlarged fragmentary horizontal detailed sectional view taken as indicated by line 6—6 on Fig. 4 with the brush removed. Fig. 7 is a perspective view of the cosmetic insert or cartridge. Fig. 8 is a fragmentary view with certain parts in longitudinal cross section illustrating a slightly modified form of the invention. Fig. 9 is an enlarged plan view of another embodiment of the invention with the cover in the open position. Fig. 10 is a vertical detailed sectional view of the structure shown in Fig. 9 showing the cover closed and illustrating the brush and handles in elevation, and Fig. 11 is a horizontal detailed sectional view of the body with the brush removed, taken substantially 15 as indicated by line 11—11 on Fig. 10.

The improved cosmetic applicator of the present invention may be said to comprise, generally, a body 10 having a handle 11, a reflecting element or mirror 12 on the body 10, an insert or filler 13 20 of cosmetic replaceably contained in the body 10 and a brush 14 removably carried by the body 10 and handle 11 for applying the cosmetic.

The body 10 is provided to contain the cosmetic insert or filler 13 and to carry the mirror 12 and 25 the other elements of the device. In the preferred construction the body 10 includes an outer member 15 and an inner member 16. The outer body member 15 is a generally cylindrical part formed of sheet metal or the like and finished 30 or plated as desired. The outer body member 15 is provided, at what I will consider its lower side, with an inwardly projecting annular flange 17. A cut or gap 18 is provided with the side wall of the outer body member 10. The gap 18 terminates at the flange 17 and does not divide or 35 cut through the flange. The inner member 16 of the body 10 is secured within the outer member 15. The member 16 is generally cylindrical or annular and is proportioned to closely fit 40 within the cylindrical wall of the outer member 15. In the preferred construction illustrated the member 16 is channel-shaped or U-shaped in transverse cross section having spaced inner and outer cylindrically curved walls 19 and 20 and an 45 upper end connecting said walls.

The inner body member 16 may be secured in the outer member 15 in any suitable manner. In the construction illustrated an annular groove is provided in the interior of the outer member 15 50 and an external bead 21 is provided on the outer wall 20 of the member 16 to cooperate with the groove to hold the inner member in the outer member. The parts are proportioned so that the lower side of the inner member 16 is spaced above 55

the flange 17. The inner body member 16 is split or provided with a lateral opening or gap 22 that is aligned with the gap 18 in the outer body member 15.

5 The invention preferably includes a cover 23 for closing the upper side of the body 10. As illustrated in the drawings the cover 23 may be a disc-like member having a suitably shaped or ornamented upper side. The cover 23 is pivotally 10 or swingably secured to the upper wall of the inner body member 16 by a hinge pin 24. The hinge pin 24 is shiftably and turnably received in registering openings in the cover 23 and the upper wall of the member 16 and projects down into 15 the member 16. The opposite ends of the pin 24 are provided with heads and the upper head of the pin cooperates with the upper side of the cover 23. A helical spring 25 surrounds the inwardly projecting portion of the pin 24 and is 20 arranged under compression between the under surface of the member 16 and the lower head of the pin 24 to exert an inward force on the pin and the cover 23. The cover 23 is proportioned so that its marginal or peripheral portions over- 25 lie the upper side of the body member 16 when in the closed position.

Means is provided for yieldingly or releasably retaining the cover 23 in the closed position. A curved or concentric downwardly projecting ridge 30 or flange 26 is provided on the under side of the cover 23 and is adapted to cooperate with the inner surface of the wall 19. The flange 26 is of the greatest thickness diametrically opposite the pivotal connection of the cover 23 with the body 35 16 and tapers away from this point to disappear or merge with the under side of the cover 23 adjacent the pivotal connection of the cover with the body 10. When the cover 23 is in the closed position the flange 26 cooperates with the wall 40 19 to hold the cover closed. When the cover 23 is deliberately or intentionally pivoted to the open position the tapering flange 26 rides over the upper surface of the body 10, the spring 25 yielding to allow for the required upward tilt- 45 ing of the cover 23. When the cover 23 is returned to its closed position the flange 26 automatically snaps into cooperation with the internal surface of the wall 19 under the action of the spring 25 acting on the cover 23.

50 The handle 11 projects laterally or radially from the body 10 to facilitate the handling or manipulating of the device and to assist in supporting the brush 14. The handle 11 is an elongate member having its inner end fixed to the 55 outer body member 15. In the drawings I have shown the inner end of the handle 11 welded to the body 10 at 27. The longitudinal axis of the handle 11 is preferably in central longitudinal alignment with the above described gaps 18 and 60 22 in the wall of the body 10. In practice the handle 11 may be of any suitable configuration. In the typical case illustrated the upper side of the handle 11 is flat and horizontal considering the device to be in the position illustrated in Fig. 65 4 and the under side of the handle is rounded or convex. The handle 11 may be tapered or of outwardly diminishing thickness as clearly illustrated in the drawings.

70 The reflecting element or mirror 12 is provided on what I have termed the under side of the body 10. The mirror 12 may be formed of plated or polished metal or may be constructed of silvered glass, as illustrated in the drawings. In accordance with the invention the mirror 12 is disc- 75 shaped and is proportioned to be passed into the

outer body member 15 from its upper side prior to the insertion of the inner body member 16. The mirror 12 has its lower surface resting against the flange 17 and the flange serves to prevent outward movement and displacement of the mirror. 5 It is preferred to arrange a thin metal shim 28 against the inner or upper face of the mirror 12 to protect the silvering of the mirror and to prevent breakage of the mirror. When the inner body member 16 is in place its lower sides or 10 edges cooperate with the shim 28 to hold the mirror 12 firmly in place. It is to be observed that the mirror 12 closes the lower side of the body 10 and is of substantial diameter. The body 10 provided with the laterally projecting handle 11 15 and carrying the mirror 12 on its under side resembles in appearance a typical hand mirror when viewed as in Fig. 1.

The insert or filler 13 of cosmetic is contained in the body 10 to be conveniently accessible and 20 to be protected against loss and breakage. The filler 13 includes a holder or cup 29 having a closed bottom and an open upper side or top. The cup 29 is proportioned and shaped to rather closely fit within the inner wall 19 of the body member 25 16. When the cup 29 is in place its bottom rests on the mirror shim 28 and its upper edge is below the upper surface of the body 10 to be clear of the flange 26 on the cover 23. The side wall of the cosmetic cup 29 has a lateral opening or gap 30 35 registering with the gap 22 in the inner body member 16. It is preferred to provide means for removably holding the cosmetic cup 29 in place to prevent its accidental displacement from the body 10. In the construction illustrated the wall 35 19 has indentations 31 spaced at opposite sides of the gap 22 and the side wall of the cosmetic cup 29 has projections 32 cooperating with the indentations 31 to removably hold the cup in place.

40 The cup 29 contains a suitable or selected cosmetic 33. The cup 29 may contain cake mascara, cream mascara, eye shadow, cream or cake rouge, face powder in cake form, etc. The cosmetic 33 may entirely fill or occupy the cup 29 with the 45 exception of a space or socket 34 molded or otherwise formed in the cosmetic. The socket 34 extends radially inward from the gap 30 to adjacent the center of the cup 29. The socket 34 is provided to receive a part of the brush 14 as will 50 be subsequently described. It will be observed that the cosmetic 33 is entirely enclosed and protected when the cover 23 is in its closed position and is freely accessible for use when the cover is opened.

55 The brush 14 is provided to facilitate the application of the cosmetic 33. The brush 14 includes an elongate handle 36 and tufts of bristles 37, or the like, on the inner end of the handle. In the preferred construction the bristles 37 are set 60 or secured in a holder 38 and the holder is set in a slot 39 in the inner end of the handle 36. The inner part of the brush handle 36 is adapted to be received in the gaps 18, 22 and 30 so that the handle and the bristles 37 may project into the 65 socket 34 in the cosmetic 33. When the brush 14 is in its normal position the handle 36 is arranged longitudinally at the upper side of the body handle 11. The outer portion of the brush handle 36 is reduced in size or diameter to leave or provide an outwardly facing annular shoulder 40. It is preferred to make the brush handle 36 cylindrical and to provide a groove 41 in the flat upper side of the body handle 11 to partially receive the brush handle 36. The groove 41 is shaped 75

to receive the graduated handle 36, having a shoulder 42 intermediate its ends that faces inwardly. The shoulder 42 is adapted to cooperate with the shoulder 40 on the brush handle 36. 5 When the brush handle 36 is received in the groove 41 its projecting upper portion presents a curved or convex surface to complement the curved under surface of the body handle 11.

A socketed head or cap 43 is secured to the outer 10 end of the brush handle 36. In practice the cap 43 may be press-fitted on an end part of the handle 36. The cap 43 may be generally spherical in shape and its inner side is provided with a socket 50 to receive the brush handle 36 with substantial clearance. The end portion of the brush handle 36 projecting into the cap 43 is reduced in diameter to provide an outwardly facing shoulder 44. A washer 45 is shiftable on the reduced end portion of the brush handle 36 and is 15 adapted to engage against the shoulder 44. Yielding means or spring means is provided in the cap 43 to assist in removably retaining the brush 14 in position on the body 10 and handle 11. This spring means may comprise a body 46 20 of resilient material, such as rubber, rubber composition, or the like, provided on the reduced end portion of the handle 36 to occupy a substantial portion of the socket 50. The washer 45 bears against the outer or exposed face of the resilient 25 body 46 and is adapted to cooperate with the outer end of the handle 11.

The parts are proportioned so that the resilient body 46 is under compression when the brush 14 is in position with its shoulder 40 in cooperation 30 with the shoulder 42. The resiliency of the rubber body 46 serves to maintain the shoulder 40 in secure engagement with the shoulder 42 to retain the brush 14 in place. As best illustrated in Fig. 4 of the drawings, the washer 45 bears 35 against the end of the handle 11 and is clear of the shoulder 44 when the shoulders 40 and 42 are in engagement and the resilient body 46 is under compression. The engagement of the washer 45 with the end of the handle 11 and the cooperation of the shoulders 40 and 42 assists in retaining the brush 14 in place on the device. When the brush 14 is in its normal position the outer end portion of the body handle 11 is received in the socket 50 and the cap 43 may engage 40 the handle 11 to prevent the brush from being accidentally displaced from the handle 11 and the body 10.

To remove the brush 14 an inward force may be applied to the brush handle 36 to further compress the resilient body 46 and thus free the shoulder 40 from the shoulder 42 so that the brush handle 36 may be moved laterally or upwardly to where the shoulder 40 will clear the shoulder 42. Another manner of removing the brush 14 is to merely exert a downward force on the cap 43 to move or pivot the handle 14 on the handle 11 to move the shoulder 40 out of engagement with the shoulder 42 and thus free the brush for removal. To re-apply the brush 14 to the body 10 and handle 11 the handle 36 is passed through the gaps 18, 22 and 30 to introduce the bristles 37 to the socket 34 and the handle 36 is entered or started in the groove 41. An inward force is then applied to the cap 43 to compress 55 the resilient body 46 against the end of the handle 11 through the medium of the washer 45 and thus bring the handle 36 to the position where its shoulder 40 may swing or snap into engagement with the shoulder 42.

70 It is believed that the utility and practicability

of the device illustrated in Figs. 1 to 7, inclusive, of the drawings will be readily understood from the foregoing description. When the device is being carried about the cover 23 may be in the closed position and the brush 14 may be in the normal position illustrated in Figs. 2, 3 and 4 of the drawings. The cover 23 serves to prevent the displacement of and damage to the cosmetic 33 and prevents the hands and clothing from being soiled by the cosmetic. The cover 23 extending over the inner portion of the brush 14 protects the bristles 37 and assists in preventing loss or displacement of the brush 14. The mirror 12 is at the exterior of the body 10 and is always available for use.

When it is desired to apply the cosmetic the cover 23 is first swung to the open position and the brush 14 is then disengaged from the body 10 and handle 11 in the manner described above. The bristles 37 may be brushed across the face of the cosmetic 33 to receive a suitable amount of the cosmetic and the brush 14 may be employed to apply the cosmetic. Where circumstances make it necessary or desirable the mirror 12 may be utilized as an aid in applying the cosmetic. The cover 23 may be closed and the device may be held and manipulated in such a manner that the mirror 12 is an aid in the application of the cosmetic by means of the brush 14. After use the brush 14 may be easily and quickly re-sealed to the body 10 and handle 11 in the manner described above, to be immediately available for subsequent use. When the cosmetic 33 becomes exhausted or when it is desired to replace or exchange the cosmetic the filler 13 may be removed from the body 10 and a new or replacement cosmetic filler inserted in the body.

Fig. 8 of the drawings illustrates a slightly modified form of brush holding or retaining means. In this form of the invention the above described rubber body 46 is replaced by a helical compression spring 51. The spring 51 is arranged in the socket 50 of the cap 43 and surrounds the reduced end portion of the brush handle 46. The spring 51 is under compression between the bottom wall of the socket 50 and a washer 45a. The washer 45a surrounds the reduced end portion of the brush handle 36 and is adapted to bear against the shoulder 44 to limit expansion of the spring 51 when the brush 14 is disengaged from the handle 11. The washer 45a has a tubular part 52 surrounding the reduced end portion of the brush handle 36 and received in the spring 51 with clearance. The tubular part 52 slidably arranged on the reduced portion of the handle 36 serves to prevent tilting of the washer 45a. The spring 51 arranged under compression between the bottom wall of the socket 50 and the washer 45a has the same function as the rubber body 46, that is, it yieldingly urges the washer 45a against the outer end of the body handle 11 to maintain the shoulders 40 and 42 in engagement and thus removably hold the brush handle 14 on the body handle 11.

Figs. 9 to 11, inclusive, illustrate a form of the invention embodying a cosmetic insert or filler 13a carrying a plurality of supplies of cosmetics. The body 10, the handle 11, the mirror 12, the brush 14 and the means for removably retaining the brush on the body 10 may be identical with the corresponding elements of the previously described form of the invention.

The filler 13a includes an outer cup or holder 60 and inner cups 58 in the holder 60. The holder 60 is proportioned and shaped to be received with-

in the inner wall 19 of the body member 16. The bottom of the holder 60 may rest on the shim 28 and the upper edge of the holder is spaced below the top of the body 10. The holder 60 may be removably retained in the body 10 in the same manner as the above described cup 29. The side wall of the holder 60 has an opening or gap 30^a registering with the gap 22. A raised web portion or partition 61 is provided in the holder 60. The partition 61 may be an integral part of the holder 60 extending upwardly from the bottom of the holder and joining the side wall of the holder. The partition 61 is diametrically opposite the gap 30^a and is radial, extending from adjacent the center of the holder to the side wall of the holder. The opposite side walls of the partition 61 are preferably flat and substantially parallel.

In accordance with the invention means is provided on the top or upper side of the partition 61 to clean the brush 14 or to remove excess cosmetic from the bristles 37 of the brush. This means comprises a plurality or series of wiping or scraping edges 62 formed by making multiplicities of cuts 63 in the top wall of the partition 61 and bending the material of said wall upwardly at corresponding edges of the cuts. The edges 62 are such that they effectively scrape or remove cosmetic from the bristles 37 when the bristles 30 are drawn or wiped across the top of the partition 61. The cosmetic thus removed from the brush bristles 37 may fall through the cuts 63 into the hollow partition 61 or may be wiped from the top of the partition.

35 The inner holders or cups 58 are provided to contain cosmetics and are carried within the holder 60. The cups 58 are segmental in shape having curved outer walls conforming with the side wall of the holder 60 and having straight 40 vertical inner walls 64. These inner walls 64 of the cups 58 cooperate with the side walls of the partition 61. The cosmetic cups 60 may be removably press-fitted in the holder 60. It will be seen that the engagement of the straight walls 45 64 with the sides of the partition 61 holds the cups 58 spaced apart, leaving a space or socket 65 for receiving the inner portion of the brush 14 and the brush bristles 37. The cups 58 are open topped and may contain cakes or supplies 50 of cosmetics. In accordance with the invention the cups 58 may contain cosmetics of different shades, types or characters.

The operation or use of the form of the invention illustrated in Figs. 9, 10 and 11 is substantially the same as that of the previously described 55 form of the invention. The brush 14 may be readily removed from the body 10 and employed to apply the cosmetics contained in the cups 58. Following the use of the brush for applying the cosmetic contained in one of the cups 58 the brush bristles 37 may be wiped or drawn across the edges 62 for the purpose of removing the remaining or excess cosmetic from the brush bristles. This leaves the brush clean for the subsequent application of the cosmetic contained in the other cup 58, if this is desired. Thus the form of the invention illustrated in Figs. 9, 10 and 11 60 contains or provides two different cosmetics and an effective means for readily applying the same in succession.

The ornamental design of the device herein described and claimed forms the subject matter of my co-pending application for Design Patent Serial No. D-81,385, filed November 26, 1938.

Having described only typical preferred forms and applications of my invention, I do not wish to be restricted or limited to the specific details herein set forth, but wish to reserve to myself any variations or modifications that may appear to those skilled in the art or fall within the scope of the following claims:

Having described my invention, I claim:

1. A device of the character described including a body, a cosmetic container in the body, a brush removably carried by the body for applying the cosmetic, and means on the body for removing the cosmetic from the brush. 10

2. A device of the character described comprising a body containing a cosmetic, a handle secured to the body and projecting therefrom, a brush for applying the cosmetic and having a handle extending along a face of the body handle, and means removably retaining the brush handle on the body handle. 15

3. A device of the character described comprising a body containing a cosmetic and having a lateral opening to its interior, a handle projecting laterally from the body, a brush having a handle adapted to extend along the body handle and bristle means adapted to be received in said opening, and means removably securing the brush in the position where its handle is held along a side of the body handle and its bristle means is received in said opening. 25

4. A device of the character described comprising a cup-like body having a lateral opening, a cosmetic holder in the body having a lateral opening aligned with the first named opening, a lateral handle projecting from the body, a brush for applying the cosmetic comprising a handle and bristle means on the handle, and releasable means retaining the brush in the position where its handle lies against the first named handle and its bristle means is received in said openings. 35

5. A device of the character described comprising a cup-like body having a lateral opening, a cosmetic holder in the body having a lateral opening aligned with the first named opening, a lateral handle projecting from the body, a brush for applying the cosmetic comprising a handle and bristle means on the handle, and means releasably securing the brush handle to the first named handle to extend longitudinally thereof and extend through said openings so that the bristle means is received in the holder. 45

6. A device of the character described comprising a cup-like body having a lateral opening, a cosmetic holder in the body having a lateral opening aligned with the first named opening, a supply of cosmetic in the holder having a socket communicating with said lateral openings, a handle projecting from the body at the opening therein, a brush for applying the cosmetic including a handle, and bristle means on an end of the handle, and means for removably holding the brush in the position where its bristle means is in said socket and its handle lies against the first named handle in substantially parallel relation thereto. 55

7. A cosmetic applying device including a body having a lateral opening, a supply of cosmetic in the body having a socket communicating with said opening, an elongate handle projecting from the body, a brush for applying the cosmetic comprising an elongate handle and bristle means on an end of the brush handle, and releasable means retaining the brush in a position where the brush handle lies longitudinally against a side of the 60

first named handle and extends into said opening and the bristle means is received in the said socket.

8. A cosmetic applying device including a body having a lateral opening, a supply of cosmetic in the body having a socket communicating with said opening, an elongate handle projecting from the body, a brush for applying the cosmetic comprising an elongate handle and bristle means on an end of the brush handle, and releasable means retaining the brush in a position where the brush handle lies longitudinally against a side of the first named handle and extends into said opening and the bristle means is received in the said socket, said releasable means comprising engaging shoulders on said handles, and resilient means carried by the brush handle and cooperating with the said first named handle to hold the shoulders in engagement.

9. A cosmetic applying device including a body having a lateral opening, a supply of cosmetic in the body having a socket communicating with said opening, an elongate handle projecting from the body, a brush for applying the cosmetic comprising an elongate handle and bristle means on an end of the brush handle, and releasable means retaining the brush in a position where the brush handle lies longitudinally against a side of the first named handle and extends into said opening and the bristle means is received in the said socket, said resilient means comprising engaging oppositely facing shoulders on the said handles, a shiftable part on the brush handle bearing longitudinally against the said first named handle, and resilient means urging said part against said first named handle.

10. A cosmetic applying device including a body having a lateral opening, a supply of cosmetic in the body having a socket communicating with said opening, an elongate handle projecting from the body, a brush for applying the cosmetic comprising an elongate handle and bristle means on an end of the brush handle, and releasable means retaining the brush in a position where the brush handle lies longitudinally against a side of the first named handle and extends into said opening and the bristle means is received in the said socket, said resilient means comprising engaging oppositely facing shoulders on the said handles, a shiftable part on the brush handle bearing longitudinally against the outer end of the first named handle, and a body of rubber on the brush handle urging the said part against the end of said first named handle.

11. In a device of the character described, a holder including a bottom and a side wall, said circular side wall having an opening, and a substantially disc shaped body of cosmetic in the holder having a socket in its periphery communicating with the said opening.

12. In a device of the character described, a holder including a bottom and a substantially circular side wall, said side wall having an opening, and a cake of cosmetic contained in the

holder and having a passage extending radially inward from said opening.

13. A device for applying cosmetic comprising a hollow body having an open top and a lateral opening in its side, a shiftable cover for the top of the body, a reflector on the bottom of the body, a handle projecting from the side of the body at said opening, a removable cosmetic holder in the body having an opening in its side registering with the first named opening, a brush for applying the cosmetic comprising an elongate handle, and bristle means on the inner end of the handle, and means removably holding the handle of the brush against a side of the first named handle to pass through said openings so that the bristle means is received in the holder.

14. A cosmetic applying device including a body having a lateral opening, a supply of cosmetic in the body having a socket communicating with said opening, an elongate handle projecting from the body, a brush for applying the cosmetic comprising an elongate handle and bristle means on an end of the brush handle, and releasable means retaining the brush in a position where the brush handle lies longitudinally against a side of the first named handle and extends into said opening and the bristle means is received in the said socket, said resilient means comprising engaging oppositely facing shoulders on the said handles, a shiftable part on the brush handle bearing longitudinally against the outer end of the first named handle, and a spring urging said part against the end of the first named handle.

15. A device of the character described comprising a body, a holder in the body, a partition in the body, cosmetic containers in the holder spaced apart by the partition to leave a space in the holder, the body having an opening aligned with the space, a brush removably carried by the body and having bristle means received in said space and opening, and means on the partition for removing cosmetic from the bristle means.

16. A cosmetic applying device comprising a hollow body having a bottom wall and a side wall, cosmetic containers arranged in the body to rest on the bottom wall and spaced apart to leave a space in the body, the side wall of the body having an opening communicating with the space, a brush having a bristle head, and means removably holding the brush on the body where it extends through said opening to have its bristle head in said space.

17. A cosmetic applying device comprising a body, cosmetic containers in the body spaced apart to leave a space in the body, the wall of the body having an opening communicating with the space, a handle on the body projecting outwardly in alignment with the space and opening, a brush having a handle, and means removably securing the brush in the position where it extends through the opening into the space and projects outwardly from the body to have its handle in substantially parallel relation to the body handle.

MONA V. EASTLEY.
